UNITED STATES PATENT OFFICE.

BENJAMIN H. McCALL, OF PORT GAMBLE, WASHINGTON.

LUMBER-STACKING DEVICE.

1,186,922.

Specification of Letters Patent. Patented June 13, 1916.

Application filed April 14, 1915. Serial No. 21,278.

To all whom it may concern:

Be it known that I, BENJAMIN H. McCALL, a citizen of the United States, and a resident of Port Gamble, in the county of Kitsap and State of Washington, have invented certain new and useful Improvements in Lumber-Stacking Devices, of which the following is a full, true, and exact specification.

My invention relates to lumber piling devices and has for its principal objects; to provide a device which will save time and labor in stacking lumber upon trucks and the like and which will assist the workman doing the stacking to build up a stack which is plumb, true and of a predetermined shape and size without any calculation being necessary on the part of the workman.

It will be understood that the stacking of lumber is done by cheap and unskilled labor which is frequently not capable of building up a plumb and accurate stack of lumber without wasting such time in so doing. By using my device, it is calculated that a given laborer will stack much more lumber in a day and that the stacks will all be plumb and of uniform size and shape as is very necessary when the lumber is being stacked onto trucks for placing in dry kilns and the like. The space allowed between any two lines of stacks in a dry kiln is very small and if the stacks are not plumb or if the separating strips between the layers of lumber are allowed to project beyond the side of the stack, it is quite likely that the stacks in one line will engage those in the adjacent line and thus render the stacks inseparable and in other ways cause delay and trouble in handling the stacks. It will be further understood that in stacking lumber upon trucks to be kiln dried, that it is important that the separating strips shall be in vertical alignment one above the other so as to hold the lumber flat and true against warping during the process of drying. It is important to prevent the lumber from warping and checking, as otherwise there is considerable loss in trimming. In this connection it is possible with my device to build up both ends of a stack square instead of allowing one end to tail out in a ragged fashion, due to the various lengths of lumber being piled in a single stack.

Other objects will appear as my invention is more fully explained in the following specification, illustrated in the accompany-

ing drawings and pointed out in the appended claim.

In the drawings, Figure 1 is a side elevation of my device shown in use in the operation of stacking lumber, with parts broken away. Fig. 2 is a plan view of Fig. 1 with parts broken away. Fig. 3 is a fragmentary plan of a preferred form.

Referring more particularly to the drawings, Figs. 1 and 2, numerals 1 and 2 indicate trucks which are adapted to run upon rails 3 and which are arranged as shown with cross bunkers 4 upon them. The lumber 5 is piled upon the bunkers with separating strips 6 between each layer of lumber and directly above the bunkers. All of the above indicated members are common.

My device consists of the following described members.

7 indicates vertical corner posts, one at each corner of the proposed stack of lumber. They may be secured to a floor or driven into the ground. The posts 7 are channeled as at 8 and 9 to receive end gates 10 and side gates 11 respectively, which are adapted to slide vertically within the said channels. The end gates are suspended by cables 12 which pass over sheaves 13 at the top of posts 7 and which are provided with counter weights 14, the counter weights being preferably heavier than the gates. The side gates are suspended by cables 15 which pass over sheave wheels 16 and which are provided with counter weights 17 which are also preferably heavier than the gates. The gates are all raised by the counter weights and lowered manually, the side gates being held at the desired place by any convenient means, such as pegs 18 which may be thrust into holes bored in posts 7. The side gates 11 may be of any desired depth, but preferably the depth of about 10 or 12 tiers of lumber. The end gates are somewhat thinner at the ends than the width of the channels 8 and are provided with wedges 19 which are arranged to be forced between outer ends of the gates 10 and the edges of the channels 8 by means of connecting rods 20, and bell crank levers 21, the former of which connect the wedges to the bell crank levers which, upon being set as shown, force the wedges into locked position.

When the levers are thrown to either side, the wedges are withdrawn and the gates released which is necessary when it is desired

to raise or lower them. The wedges perform an additional function in that they force the said gates inwardly when locked and that upon being released, the gates are allowed to fall back slightly from the end of the stack of lumber which allows the gates to be raised more easily. The end gates are preferably somewhat deeper than the side gates as they are otherwise smaller and lighter than the side gates. The side gates may be stiffened by truss rods 22 if desired and are provided with vertical strips 23 which are used to butt the spacing strips 6 against in order to more easily aline them vertically. The end gates have similar strips 24 which aline the corners of the stack of lumber. Upon starting a stack of lumber, the gates are lowered until their lower edges are below the lowest tier of lumber and the placing of lumber commenced. In placing the various pieces of lumber, all ends are pushed up against the end gates and the side pieces are lined up with vertical strips 23 on the side gates. After each layer or tier of lumber is placed, a layer of spacing strips 6 are placed and lined up against the vertical strips 23. After the lumber has been stacked as described, to the top of the side gates, they are raised a distance equal to their depth and the stacking proceeds.

When the tops of the end gates are reached, the wedges 19 are withdrawn and the end gates raised a distance equal to their depth at which time the said gates are locked in place by the wedges 19. The posts 7 are of such height that after the stack has reached its full height, the gates may all be shoved up above the completed stack which is now free to be shoved forward along the rails 3 and into the dry kiln without the necessity of removing any posts, gates or other parts of my device. Another stack may now be started within my stacking device as previously described.

Referring to Fig. 3, numeral 25 indicates side posts which are hinged as at 26, to the floor 27 and which may be used on one side instead of a side gate if so desired. After the stack is completed, the posts 25 are folded down upon the floor out of the way of the stack.

While I have shown a particular form of my invention, I am aware that many minor changes therein, will readily suggest themselves to others skilled in the art without

departing from the spirit and scope of the invention, and I therefore, desire to avoid being limited to the exact form shown and described, except as defined in the appended claim.

Having described my invention, what I claim as new and desire to protect by Letters Patent, is—

In a lumber stacking device, the combination of a plurality of vertically channeled guide posts arranged in the form of a rectangle and resting on a floor, a pair of oppositely disposed side gates which are adapted to move vertically in channels in the said guide posts and a pair of similarly disposed end gates which are adapted to move similarly in other channels in the said posts, the two pairs of said gates forming a hollow rectangle within which and against the inner side of which lumber is piled in the form of a stack, means for raising the said gates vertically in the said channels, side gate holding means whereby the said gates may be held at any desired point in their travel, end gate holding and wedging means, said means including wedges slidably secured to the backs of the gates and adapted to be thrust between the backs of the said gates and the outer edge of the channels in which the said gates slide, whereby the said gates may be thrust and held against the inner sides of their respective channels while the lumber is being stacked against them and whereby when the wedges are withdrawn, the said end gates are free to move outwardly slightly from contact with the lumber of the stack and may be more easily raised on account of the said release of contact, oppositely disposed vertical strips upon the inner sides of the said side gates, whereby the separating strips between adjacent layers of lumber in a stack are maintained in vertical alinement one above the other, vertical strips upon the inner side of the end gates one at either end of the said gates, whereby the edges of the pieces of lumber which are on the outside of the stack are kept in vertical alinement, and the corners of the stack are kept straight and plumb.

BENJAMIN H. McCALL.
